UNITED STATES PATENT OFFICE

2,604,639

HYDRAULIC HOSPITAL BED LIFT

Jack L. Killifer, Burbank, Calif.

Application January 18, 1950, Serial No. 139,303

1 Claim. (Cl. 5—63)

1
This invention relates to beds especially adaptable for hospital use, and more particularly to a hospital bed having a hydraulic hospital bed lift system operatively attached thereto.

An object of this invention is to provide a hospital bed with telescopic leg members which are selectively operatively controlled hydraulic means.

A further object of the invention is to provide hydraulically operated means for selectively raising and lowering the telescopic legs of a hospital bed in accordance with a desired setting of a valve mechanism.

Yet another object of the invention is to provide a valve mechanism for regulating the flow of hydraulic fluid to hydraulically actuated cylinders so as to adjust a hospital bed to a desired position.

Due to the fact that doctors and nurses can more easily perform their necessary tasks upon a patient when the patient is reclining on a substantially higher plane than would be easy for the patient to raise or lower himself or herself to, it is a further object of the invention to provide means easily operated by a patient to raise or lower a hospital bed on which he is reclining.

Still further objects of the invention reside in the provision of a hydraulic hospital bed lift system that is strong, durable, highly efficient in operation, simple in construction and design, capable of being easily and cheaply manufactured, and easily operated by a patient lying in the bed.

These, together with the various ancillary objects of the invention which will become apparent as the following description proceeds, are attained by this hydraulic hospital lift system, a preferred embodiment of which has been illustrated in the accompanying drawings, by way of example only, wherein:

Figure 1 is a side elevational view of the hydraulic operated system as used on a hospital bed;

Figure 2 is a vertical sectional view as taken along line 2—2 in Figure 1;

Figure 3 is an enlarged vertical sectional view of the hydraulically actuated extensible leg members comprising one element of the present invention;

Figure 4 is a schematic diagram showing how the valve member actuates the telescoping leg members;

Figure 5 is a series of schematic diagrams illustrating how certain combinations of the hospital legs may be selectively actuated;

2
Figure 6 is a top plan view of the valve means for selectively actuating the hospital bed lift;

Figure 7 is an elevational view showing schematically the combination between the pump and the valve member of the hydraulic system, and

Figure 8 is another enlarged vertical sectional view showing another form of hydraulically extensible leg members.

With continuing reference to the accompanying drawings wherein like reference numerals designate similar parts throughout the various views, reference numeral 10 generally designates a hospital bed upon which the telescoping legs 12 are adapted to be secured. It is quite possible to easily adapt existing hospital beds for use with the invention by merely cutting or sawing the lowermost portions of the legs therefrom. Then it is merely necessary to secure by screws 14 or other suitable means the tubular shell 16 to the remaining portions of the legs.

The tubular shell 16 is internally threaded as at 18 and a hydraulic cylinder 20 is provided with a portion 22 threadedly engaging the threaded portions 18 of the tubular shell.

25 The hydraulic cylinder 20 is provided with a reservoir chamber 24 to which is secured through a passage in the shell 16 a conduit 36. A partition 28 having an aperture 30 therethrough is provided between the reservoir chamber 24 and the piston or main chamber 32. The piston 34 is slidably mounted within the main chamber 32 and a piston rod 26 is rigidly secured thereto. Threadedly secured to the lower end of the cylinder 20 is a gland seal bearing nut 38 within which the piston rod 26 is slidably emplaced. The lowermost end of the piston rod 26 is threaded as at 40 and is secured to an internally threaded portion 42 of a substantially cylindrical member 44 that is slidably mounted between the shell 16 and the cylinder 20. If desired a caster 46 may be secured to the lowermost portion of the cylindrical member 44.

45 Each of the conduits 36 is secured to a casting 48 which is mounted by suitable clips to the headboard of the bed 10. Connected to the casting 48 is an inlet supply conduit 50 (Figure 7) which is connected to a reservoir 52. A valve 54 is provided intermediate the casting and the reservoir. Likewise a by-pass conduit 58 is provided for the usual purpose. A pump 56 is secured in such operative manner as to readily cause a flow of fluid from the reservoir 52 upwards of the inlet supply conduit 50. The inlet conduit 50 is in communication with an enlarged conduit 60 in a drum 62, shown in skeleton out-

line in Figure 4, rotatably journaled in the casing 48. A plurality of radial passageways 64 are provided in the ends of the drum 62 for selective alignment with the desired conduits 36. A handle indicator 66 on the outside of the casing 48 is secured on a shaft which is rigidly secured to the drum 62. The shaft is generally indicated by reference numeral 68. A plurality of indicia are marked on the face of the casing 48 to indicate the following possible 10 operations of the system. As shown in Figure 7, the symbol "N" indicates that none of the apertures 64 are in alignment with the conduits 36. Therefore none of these legs will be actuated. When the indicator 66 is rotated to the 15 full position, a conduit 64 is in communication with each of the conduits 36. When the indicator 66 is rotated to "R," the rear legs as indicated in "A" in Figure 5 will be actuated to raise the rear of the bed. As shown at "B" in Figure 5 when the indicator 66 is rotated to "F" the front legs are actuated. The other possible combinations of legs are the left and right sides which are actuated respectively as shown at "C" and "D." Obviously, the apertures 64 are suitably spaced to permit these possible combinations.

Referring now to Figure 8, it will be seen that the hydraulically extensible leg assembly may be readily used for various other purposes such as tables, pianos, etc. In this form the assembly generally consists of the leg 80 wherein is inserted a tubular shell 82. The hydraulic cylinder 84 has the piston 86 slidably mounted therein. A sliding sleeve 88 is provided between the 35 cylinder 84 and the shell 82 and is attached adjacent the bottom end of the piston 86. A castor 90 is rotatably secured to the bottom end of the piston 86. When hydraulic pressure is released the castor 90 will disappear inside the shell 82 and bed post or leg 80.

Since from the foregoing the construction and advantages of this hydraulic hospital bed lift are readily apparent, further description is believed to be unnecessary.

However, since numerous modifications and uses will readily occur to those skilled in the art after a consideration of the foregoing specification and accompanying drawings, it is not intended to limit the invention to the precise embodiments and uses shown and described, but all suitable modifications and equivalents may be resorted to which fall within the scope of the appended claim.

Having described the invention, that is claimed as new is:

A hydraulic bed lift system comprising a plurality of selectively hydraulically extensible leg members, each of said leg members including a tubular shell, a hydraulic cylinder secured within said shell, a piston slidably in said cylinder, a cylindrical support member connected to said piston slidably between said shell and said cylinder, a plurality of conduits connecting said hydraulic cylinders in each of said leg members with a casing forming part of valve means for selectively actuating said leg members, hydraulic fluid supply means connected to said casing, and means rotatably mounted in said casing for selectively connecting said conduits with said fluid supply means.
